UNITED STATES PATENT OFFICE.

JOHN H. HANKEY, OF HAGERSTOWN, MARYLAND, ASSIGNOR TO THE W. H. REISNER MFG. COMPANY, OF HAGERSTOWN, MARYLAND, A CORPORATION OF MARYLAND.

ELECTROMAGNETIC CONTROL DEVICE.

Application filed January 7, 1926. Serial No. 79,905.

My invention relates broadly to electromagnetic control systems and more particularly to the construction of an electromagnetic control device.

5 One of the objects of my invention is to provide a construction of electromagnetic control device in which the mechanical force which may be developed is relatively large for low power consumption for producing 10 pull over a relatively short stroke with substantially no time lag.

Another object of my invention is to provide an electromagnetic control device for the development of mechanical movement 15 over relatively short strokes where the initial mechanical force is relatively large, gradually decreasing in proportion to the length of the stroke.

Still another object of my invention is 20 to provide a magnetic control device in which an electromagnetic system is provided having an arcuate pole face cooperating with an arcuate armature member which is pivotally mounted on opposite sides 25 of the electromagnetic system and forms a closed magnetic circuit through the pole face, the shape of the armature and pole face being such that a relatively large attractive force may be developed at the beginning of the stroke, gradually decreasing 30 in proportion to the length of the stroke.

A further object of my invention is to provide a construction of electromagnetic control device in which a plurality of electromagnets are provided, each being provided with an arcuate shaped pole face arranged to cooperate with an arcuate shaped armature which is pivotally mounted by members extending on opposite sides of the electromagnets and connected with the core 35 members of the magnets for providing a return magnetic path which has a minimum circuitous path when the armature is attracted by the electromagnets to the limit 40 of its path of travel.

A still further object of my invention is to provide means for protecting the arcuate pole faces of an electromagnetic control device from adherence with the movable armature of the control when the armature is moved to a position where it overlaps the arcuate pole faces, reducing the circuitous magnetic circuit to a minimum.

Other and further objects of my invention will be understood from the following

specification by reference to the accompanying drawings, wherein:

Figures 1 and 2 show the two extreme positions of my magnetic control device used in connection with an organ control system; Fig. 3 is a cross-sectional view taken through the magnetic control device; Fig. 4 is a cross-sectional view taken on line 4-4 of Fig. 3; and Fig. 5 is a cross-sectional view taken on line 5-5 of Fig. 3 showing the arrangement of parts of the magnetic control device.

In the drawings which illustrate the application of my magnetic control device to an organ control reference character 1 designates the electromagnetic windings of the device which is mounted with respect to the console 2 by means of a magnetic plate 3 which is secured by screws 3^a to a block 4 in such position that normally the armature of the magnetic control device may rest directly against the side of the console at 2 when the device is in unactuated position and be brought into a position substantially at an acute angle with respect to the side of the console when the device is in actuated position. The magnet cores are designated at 5 secured to the magnetic plate 3 with the heads 9 and 10 secured thereto and provided with insulated tubular members 7 thereover on which the magnet windings are disposed. The pole tips of the magnet cores 5 are arcuate in shape as represented at 6 in such a direction that a plane tangent to any part of the surface of the pole tips 6 may intersect a plane which is aligned with the magnetic plate 3 forming the base of the electromagnetic system. I provide a non-magnetic bushing or copper ring 8 shaped to conform with the arcuate pole tips 6 which embraces the pole tips and forms bumpers against which the armature 18 of the electromagnetic control device may be moved. The rear plate 3 is provided with extensions 11 and 12 forming tongues at the outer extremities thereof between which the arms 14 and 16 of the armature member are journaled at 15 and 17. The arms 14 and 16 are of magnetic material and form a path for magnetic lines from the magnetic base plate 3 through the armature 18. The armature 18 is provided with angularly disposed cooperating faces 19 and 20 shaped in such manner that the armature may move to a position closely adjacent the magnetic pole

105
110

tips 6 at which time the armature face 19 entirely overlaps the arcuate pole tips 6 providing a minimum magnetic circuit for the lines of force through the magnetic system. 5 A shape is imparted to the armature at its face 20 such that a contacting edge is presented for line abutment with the bushings 8 on the pole tips. The armature 18 has its arcuate face 19 extending over the pole tips 10 6 forming an extremely minute air gap between the pole tips 6. The power is taken off at a point of connection 21 with the armature 18. A link such as 22 may be connected with the lug portion 21 to deliver a short 15 reciprocating stroke to any desired form of load. In Figs. 1 and 2 where the magnetic device is shown for the control of an organ, a bell crank lever 23—24 pivoted on frame member 28, is moved by the link 22 to actuate a slide 27 when the slide is in raised 20 position by energization of the circuit 32 of solenoids 26 at which time armature 25 is brought into a position in which it engages the lower end of bell crank 24 as represented 25 in Fig. 2. The slide 27 in its movement toward the right as represented in Fig. 2 engages spring member 30 actuating member 29 for operating the organ controls. The electromagnetic control in moving the slide 30 27 serves to operate the different combinations designed by tablets on the front of the console electrically instead of pneumatically. It will be understood that there are a number of slides 27 according to the capacity 35 of the instrument and requirements of the console. A circuit 31 is provided for controlling the windings 1 of the electromagnetic device, circuit connections are taken to suitable circuit closing devices and 40 energy sources for controlling any one of a number of electromagnetic devices constructed in accordance with my invention.

An electromagnetic control device constructed in accordance with the principles 45 of my invention herein has been found to operate with a high degree of efficiency. In one design of electromagnetic control device where the armature member 18 is initially spaced $\frac{1}{6}$ th of an inch from the pole tips 6, 50 with approximately 18 watts of energy, that is at a voltage of 25, and a current of .75 ampere, there has been developed a force of 24 pounds where the armature has a .8 inch stroke. The pulling force continuously 55 diminishes in proportion to the length of the stroke to a value of 8 pounds at which time the angularly disposed face 20 of armature 18 abuts against the bumper or non-magnetic spacer ring 8. The efficiency of the magnetic 60 control device is due largely to the similar shapes which are imparted to the cooperating faces 6 of the pole pieces 5 and face 19 of the armature 18. The air gap separating the arcuate pole tips 6 and the arcuate face 65 19 is extremely slight, enabling the magnetic

circuit to be readily completed through the magnetic base plate and the pivoted arms of magnetic material disposed between the magnetic base plate and the armature 18.

As heretofore pointed out the electromagnetic control device of my invention may be employed to perform a great many functions and I do not intend that my invention be limited to the use of the device in connection with organs, but that many functions may be performed by the control system. Modifications may be made in detail in the construction of the device without departing from the spirit of my invention and I intend no limitations upon the invention other than those imposed by the scope of the appended claims.

What I claim and desire to secure by Letters Patent of the United States is as follows:

1. An electromagnetic control device comprising in combination a base plate of magnetic material, a pair of core members extending from said base plate, electromagnetic windings disposed on said core members, each of said core members having arcuate shaped pole tips at the extremities thereof, a pair of arms of magnetic material pivotally mounted in said base plate on opposite sides of said electromagnetic windings, an armature carried by the extremities of said arms and having a portion thereof extending in an arc having substantially the same radius as the radius of the pole tips of said core members, whereby said armature may be moved from a position remote from said pole tips to a position substantially overlapping said pole tips for establishing a magnetic circuitous path of minimum length when said electromagnetic windings are energized.

2. An electromagnetic control device comprising in combination a pair of electromagnetic windings, core members positioned within said windings, a base plate connected adjacent the ends of said core members, said core members terminating in pole tips at the opposite ends thereof which are substantially arcuate in shape, a pair of arms of magnetic material mounted pivotally on said base member on opposite sides of said electromagnetic windings, an armature member interposed between opposite ends of said arms, said armature member having a portion thereof offset to form a limiting abutment with respect to the sides of said pole tips, with one face of said armature member shaped to correspond to the shape of said pole tips whereby said armature may be moved from a position remote from said pole tips to a position limited by the abutment of said armature with said pole tips, with one face of said armature substantially overlapping said pole tips when said electromagnetic windings are energized.

4. An electromagnetic control device comprising in combination a base plate of mag-

In testimony whereof I affix my signature.

JOHN H. HANKEY.
